A. R. KING,
ELECTRIC FLAT IRON,
APPLICATION FILED FEB. 10, 1917

1,249,638.

Patented Dec. 11, 1917.

E. W. Marshall

UNITED STATES PATENT OFFICE.

ADELE ROCKEFELLER KING, OF NEW YORK, N. Y., ASSIGNOR TO FRANCES ROCKEFELLER KING, OF NEW YORK, N. Y.

ELECTRIC FLAT-IRON.

1,249,638.

Specification of Letters Patent. Patented Dec. 11, 1917.

Application filed February 10, 1917. Serial No. 147,741.

To all whom it may concern:

Be it known that I, ADELE ROCKEFELLER KING, a citizen of the United States of America, and a resident of New York, county and State of New York, have invented certain new and useful Improvements in Electric Flat-Irons, of which the following is a specification, reference being had to the accompanying drawings, forming 10 a part thereof.

My invention relates to electric heating appliances and has special reference to electrically heated flat irons which are provided with cut-out switches for interrupting the 15 supply of energy when the iron is not in use.

One object of my invention is to provide a device of the aforesaid character that shall be simple and durable in construction, attractive in appearance and reliable in operation.

Another object is to provide a cut-out switch for closing the circuit of the heating element only when the iron is in use as determined by a downward pressure, exerted on the handle.

Another object is to provide a particularly compact cut-out for electric irons which does not necessitate the gripping of the handle by the user and which does not encumber the exterior of either the body or the handle of the iron.

Still another object is to provide a cut-out which cannot readily be rendered inoperative.

In order that my invention may be thoroughly understood I will now proceed to describe the same in the following specification and then point out the novel features 40 thereof in appended claims.

Referring to the drawings:

Figure 1 is a partially sectional elevation of an electric flat iron arranged and constructed in accordance with my invention 45 and constituting an embodiment thereof.

Fig. 2 is a circuit diagram showing the relation between the cut-out switch and the heating element.

Fig. 3 is a detail view corresponding to a 50 portion of Fig. 1 and showing a modified form of cut-out switch which is adapted to separate the contacts more rapidly when pressure is relieved from the handle and also more widely to prevent arcing at the con-

tacts and insure the interruption of the circuit.

In Figs. 1 and 2,—10 designates the base of the iron having a smoothing surface 11, and 12 designates the body section which is superposed with the heating unit or element 60 13 between the two. Any suitable heating element may be employed such as, for example, that diagrammatically represented in Fig. 2.

The body section 12 is provided with a 65 recess 14 at the top in which is disposed a cut-out switch composed of a resilient contact 15 and a cooperating stationary contact 16.

Extending upwardly from the body section 12 are studs 17 and 18 to which a handle 19 is connected. A shell or casing 20 of sheet metal is mounted on the base 10 and incloses the body section and the heating element. It is provided with openings 21 75 and 22 through which the studs 17 and 18 extend and a central hole 23 opposite the resilient contact 15.

The handle comprises a yoke 24 through which the studs 17 and 18 extend, and helical springs 25 and 26 are interposed between the yoke and the shell and surrounding the studs. They tend to elevate the handle and to hold the yoke against nuts or enlargements 27 and 28 which are affixed to the 85 studs near their upper ends.

Sleeves 29 and 30 surround the studs and guide the springs 25 and 26 which are coiled upon the sleeves.

The arrangement of parts is such that the 90 handle is pressed downwardly toward the shell and compresses the springs 25 and 26 when the iron is in use.

A push button or actuator 31 is adjustably mounted on the yoke 24 in position to extend through the opening 23 in the shell and actuate the contact member 15.

In the structure shown, the push button is formed of insulating material and is mounted on the lower end of a screw 32 which 100 extends through a tapped hole 33 in the shell and is held in place by a lock nut 34.

The terminal structure is designated 35 and may be of any suitable form.

The push button 31 is adjusted to such position that when the iron is in use the downward pressure on the handle forces the movable contact 15 into engagement with the 105

stationary contact 16 and closes the circuit through the heating element as indicated in Fig. 2.

In order to insure the interruption of the circuit for irons of varying sizes when used either on alternating or direct current circuits, the cut-out switch structure shown in Fig. 3 may be substituted for that of Fig. 1.

Having special reference to Fig. 3, this arrangement comprises a movable contact member 36 which is hinge-connected to a fixed terminal 37 by a flexible conducting section 38 or some other suitable means, and is acted upon by a spring 39 which tends to move the contact away from its coöperating stationary contact 40. A spring 41 tends to swing the inner end of the contact 36, which is closest to the flexible hinge section, downwardly and thereby widely separate the contacting parts. The point 42 where the contact is engaged by the spring 39, constitutes a pivot and since the push button 31 engages the contact 36 on the opposite side of the pivot 42 from the spring 41, a relatively small movement of the push button in a downward direction (such as is effected when the hand of the user is pressed downwardly on the handle 19), closes the contact members and completes the circuit for the heating element.

Another advantage of my iron arises from the fact that the operator may use it without pressing down on the handle and thus avoid the overheating of the iron in service. This is particularly desirable when the iron is used for light work. On the other hand, by merely pressing downwardly on the handle, the circuit is closed and the heater energized and inasmuch as the downward pressure is naturally exerted and is useful in pressing, particularly for heavy work where the energization of the iron is desirable, it is evident that the iron functions in a particularly desirable way.

Furthermore, when the hand is lifted from the handle, the current is cut off and the iron deenergized, thereby avoiding the danger of overheating and largely eliminating the fire risk.

What I claim is:

1. An electric flat iron comprising a base, a heating element, a cut-out switch, a unitary handle structure having a yoke yieldingly attached to the base and a handle grip fixed relative to the yoke, and a downwardly extending projection on the yoke adapted to

actuate the cut-out switch when downward pressure is exerted on the handle.

2. An electric flat iron comprising a base, a heating element, a shell or casing, a cut-out switch mounted within the casing, a handle, yieldingly attached to the base, and a push button on the handle adapted to extend through the shell and actuate the cut-out switch.

3. An electric flat iron comprising a base, a body, an interposed heating element, a shell or casing, a cut-out switch mounted on the body within the casing, a pair of spaced studs extending upwardly from the base, a handle having a yoke mounted to move up and down on the studs, enlargements on the studs for limiting the upward movement of the yoke, springs tending to elevate the handle and to hold the yoke against enlargements, and a push button on the yoke adapted to extend through the shell and control the cut-out switch.

4. An electric flat iron comprising a base, a body, an interposed heating element, a shell or casing, a cut-out switch mounted on the body within the casing, a pair of spaced studs extending upwardly from the base, a handle having a yoke mounted to move up and down on the studs, enlargements on the studs for limiting the upward movement of the yoke, springs tending to elevate the handle and to hold the yoke against enlargements, and a push button adjustably secured to the yoke and arranged to extend through the shell and to actuate the cut-out switch when the iron is in use.

5. An electric flat iron comprising a base, a body, an interposed heating element, a shell or casing, a cut-out switch mounted on the body within the casing, a pair of spaced studs extending upwardly from the base, a handle having a yoke mounted to move up and down on the studs, enlargements on the studs for limiting the upward movement of the yoke, springs tending to elevate the handle and to hold the yoke against enlargements, and a push button adjustably secured to the yoke and arranged to extend through the shell and to actuate the cut-out switch when a downward pressure is exerted on the handle sufficient to compress the handle elevating springs.

In witness whereof, I have hereunto set my hand this 6th day of February, 1917.

ADELE ROCKEFELLER KING.
